UNITED STATES PATENT OFFICE

90,579

DESIGN FOR A COMBINATION SURGICAL
INSTRUMENTAnnie Hall and Leonard Diamond, Harpurhey,
Manchester, EnglandApplication May 27, 1933, Serial No. 48,227, and
in Great Britain and Ireland April 3, 1933

Term of patent 7 years

To all whom it may concern:

Be it known that we, ANNIE HALL and LEONARD DIAMOND, subjects of the King of Great Britain, residing at 49 Rochdale Road, Harpurhey, Manchester, England, have invented a new, original, and ornamental Design for a Combination Surgical Instrument, of which the following is a specification, reference being had to the accompanying drawing, forming part thereof.

Fig. 1 is a perspective view of a combination surgical instrument, illustrating the design.

Fig. 2 is a cross-section on the line 2—2 of Fig. 1.

Fig. 3 is a cross-section on the line 3—3 of Fig. 1.

Fig. 4 is a cross-section on the line 4—4 of Fig. 1.

We claim:

The ornamental design for a combination surgical instrument as shown.

Signed at Manchester, England, this 19th day of May, 1933.

ANNIE HALL.
LEONARD DIAMOND.
